ELECTRICAL TIMING MECHANISM AND
SYSTEM

John W. Anderson, Gary, Ind.

Application January 26, 1931, Serial No. 511,311

22 Claims.

(Cl. 58—23)

This invention relates to electric control systems and apparatus, and particularly to electrical systems and apparatus for measuring and/or indicating time.

5 It is one of the objects of my invention to provide an improved electrical system and apparatus and method for indicating the passage of time.

Another object is to provide an improved system and apparatus for effecting and/or controlling the time-periodic operation of apparatus.

10 Another object is to provide such a system and apparatus having improved means for adjustably varying the time periods thereof.

Another object is to provide an improved electrical system and apparatus operative to energize an electric circuit periodically, for effecting and/or controlling the time-periodic operation of apparatus, and provided with improved means for adjustably varying the rate or periodicity 20 of the energization of the circuit.

Another object is to provide in a thermally actuated electric system and apparatus in which a thermo-responsive means periodically effects the energization of an electric circuit, an improved means for automatically compensating the thermo-responsive means for changes of ambient or local temperature.

Other objects will be apparent to those skilled in the art to which my invention appertains.

30 My invention is fully disclosed in the following description taken in connection with the accompanying drawing, in which:

Fig. 1 is a diagrammatic representation of an electrical apparatus and system of connections 35 therefor embodying my invention;

Fig. 2 is a view similar to Fig. 1 showing modifications.

Referring to the drawing, I have shown at 1 a bimetallic thermostatic element of rectilinear 40 form, rigidly secured at one end to a stationary base 2, and at its free end carrying a contact 3 engageable with a contact 4 on the free end of a second bimetallic thermostatic element 5, preferably identical with the element 1 and mounted, 45 at the end thereof opposite the contact 4, upon a base 6, which in turn is secured as by rivets 7—7 to a preferably resilient arm 8 rigidly connected at one end to a base 9 and adjacent its free end 10 being engaged by the end of an adjusting screw 50 11 threaded in a stationary base 12.

The base 9 is preferably disposed adjacent the contact 4 and the end 10 of the arm 8 disposed remote from the contact 4 whereby a longitudinal movement of the screw 11 will effect a much 55 smaller movement of the contact 4. Thus a very

sensitive micrometer adjustment of the position of the contact 4 toward and from the contact 3 may be effected by turning the screw 11, the resilience of the arm 8 maintaining its end 10 always in contact with the end of the screw 11.

5 The material of the elements 1 and 5 is so disposed that when responding to changes of temperature, they both tend to bend, in portions thereof remote from their bases 2 and 6 respectively, in the same direction.

10 The element 1 is provided with a heating winding 13 thereon or disposed adjacent thereto.

At 14 I have shown a thermostatic bimetallic element of generally linear form rigidly secured at one end to a base 15 and at its opposite free end carrying a contact 16, contactingly engageable with a contact 17 on the free end of a bimetallic thermostatic element 18 preferably identical with the element 14. The element 18 is mounted on the end opposite the contact 17 upon a base 19 secured as by rivets 20 to one end of a preferably resilient arm 21 rigidly connected to a stationary base 22, and at its end 23 remote from the base 22 engaged by the end of an adjusting screw 24, threaded into a stationary base 25. The element 14 has a heating winding 26. The parts 14 to 26 inclusive are generally similar to the parts 1 to 13 inclusive, above described, except for differences which will presently appear.

15 A source of electric energy such as a battery, 30 27, is connected by a wire 28 to the base 6. One end of the winding 13 is connected to the base 2, and the other end by wire 29 and a wire 30 is connected to the base 19. The winding 26 is connected at one end to the base 15, and its other 35 end is connected by a wire 31 to the source 27.

20 Current may flow from the source 27 by way of the element 5 through the contacts 3—4, element 1, heating winding 13, wire 29, element 18, contacts 16—11, element 14, winding 26, wire 31 40 back to the source 27. The current in the winding 13 heats the element 1 causing it to bend and break the circuit at 3—4, whereupon the winding 13 being de-energized, the element 1 cools off, returns to its original position and closes the 45 contact 3—4, and this action continues. Thus a succession of current impulses is sent from the source 27 over the circuit above described, which current heats the element 14 by means of the winding 26, causing the element 14 to bend and 50 break the circuit at the contact 16—17.

25 It is one of the important elements of my invention, that the elements 1 and 14 respond differently to the heat of the current impulses flowing in the circuit described, to effect a rela- 55

tively rapid periodic make-and-break at the contacts 3-4 and a relatively slow make-and-break at the contacts 16-17.

Thus a number of impulses must be sent over the circuit by the contacts 3-4 before the element 14 will bend sufficiently to break the circuit at the contacts 16-17. When the contacts 16-17 are opened, all current in the circuit ceases flowing until they close again, whereupon the relatively rapid impulses from the contacts 3-4 begin again.

This result may be effected in a number of ways. For example, the windings 13 and 26 may be alike, but the heat storage capacity of the element 14 may be greater than that of the element 1, requiring a longer period of time for it to heat sufficiently to bend it to the contact breaking degree. Again, the heating effect of a current impulse in the winding 26 may be less than that in the winding 13, whereupon again, a number of impulses will be required to break the contact at 16-17 whereas one is enough to break contact at 3-4. Other means will occur to those skilled in the art for effecting the result sought, namely that with the contacts 3-4 and 16-17 in the same circuit, the contacts 3-4 will close and open periodically a number of times, sending a number of impulses to the winding 26 before the contacts 16-17 will be opened and the current to both windings thereupon be discontinued.

A second circuit is controlled by the contacts 16-17 and comprises the winding 32 of a magnet 33, the circuit preferably including a local source of current 34, a wire 35 connected to the base 19, and a wire 36 connected to the base 15.

The magnet 32-33 operates a switch arm 37 controlling the energization of a circuit comprising a local source 38, and an electro-magnet 39. The magnet 39, upon being energized, operatively moves an arm 40 normally retracted by a spring 41 and longitudinally pulls a pawl 42 engaged with the teeth of a ratchet 43 rotatably mounted on a shaft 44. Successive energizations of the magnet 39 will cause the pawl 42 to notch the ratchet wheel 43 ahead step at a time in a well known manner. The magnet 39 will be energized by the switch arm 37 upon each energization of the winding 32 which occurs upon each closure of the contacts 16-17, energization for the winding 32 flowing from the source 34 by wire 35 through element 18, contacts 17 and 16, through element 14 and wire 36.

Switches 45, 46 and 47 may be provided to control the several circuits above described, and when these are closed, the operation of the system is as follows.

The element 1 is repeatedly bent by the heat from its winding 13, continuously opening and closing the contacts 3-4, and the current flowing through these contacts and through the winding 26 heats the element 14, and after a suitable predetermined number of impulses have flown through the winding 26, the element 14 bends sufficiently to break the contacts 16-17, whereupon the flow of current ceases. Thereupon also, the switch arm 37 moves to switch-open position as, for example, by a retracting spring 48, the winding 32 now being de-energized at the contacts 16-17. Thereupon also, the spring 41 retracts the arm 40 and moves the pawl 42 to a new notch on the ratchet 43. After an interval of time, the element 14 cools off and causes the contacts 16-17 to close, whereupon current flows

through the winding 32, attracts the switch arm 37, energizes the winding 39, attracts the arm 40 and notches the ratchet wheel 43 ahead one notch. The operation just described continues, and the ratchet wheel 43 is notched ahead one notch at the end of each period of time determined by the periodicity of the element 14.

The effect of ambient or local temperature upon the elements 1 and 14 is respectively neutralized or compensated by the elements 5 and 10, any tendency of the local temperature to bend the elements 1 or 14, say, toward the left as viewed in Fig. 1, is compensated for by the same tendency of the elements 18 and 5 to move toward the left.

The amount of heat energy supplied to the element 14 to bend it is the integration of the heat from a number of current impulses. The amount of current which flows in the circuit and through the heating windings will be determined by the voltage of the source 27, but when once established, the movement of the element 14 will be unaffected by variations of the voltage source 27. For example, if the voltage of the source 27 should decrease, the actual value of current flowing will be less but this will result in less heating effect in the winding 13 and in maintaining the contacts 3-4 closed for longer periods of time and will thus cause impulses of longer duration to flow to the winding 26. Thus on a decrease of voltage, and in a given length of time, fewer current impulses will flow to the winding 26, but they will be of longer duration, and the time current integration thereof will be constant at all voltages of the source 27.

In Fig. 1, I have shown on the shaft 44 a clock hand 50 for which there may be provided a dial not shown. Thus the system at Fig. 1 may be employed to indicate the passage of time like a clock. The rate at which the hand 50 moves around the dial will of course be determined by the rate of vibration or periodicity of the element 14. This, of course, may be predetermined within limits by the design of the parts in a well known manner and, however, may be accurately adjusted by the following means.

Upon turning the screw 11 to move the end 10 of the arm 8 toward the left, Fig. 1, the contact 8 will be moved toward the contact 3 and put some bending pressure on the element 1. This will require more heat in the winding 13 to break the contacts 3-4 and therefore cause impulses of longer duration to flow. Correspondingly, the element 14 will be heated sufficiently to break the contacts 16-17 in a shorter period of time, thus increasing the periodicity of the element 14, and moving the hand 50 faster.

Again, if the screw 24 be turned to move the element 21 toward the left, and to advance the contact 17, for any given rate of impulses from the contacts 3-4, it will require more of these impulses to bend the arm 14 to the contact breaking point and hence the periodicity of the element 14 will be slower and the hand 50 will be moved slower.

As shown in Fig. 1, the screw 24 may be provided with a dial 51 having calibration marks thereon cooperating with an index or pointer 53 stationary on the base 25. The dial 51 may be calibrated in seconds, minutes or other divisions of time, or may be calibrated in percentages of increase or decrease of periodicity of the element 14 effected by movement of the screw 24.

Similarly, the screw 11 may be provided with a calibrated dial, although not shown in the drawing.

It will be understood, of course, that the ratchet wheel 43, which is adapted to turn the shaft 44, may be employed to operate or step up apparatus of various kinds other than a clock hand and thus cause any desired operative effect of an apparatus to be brought about periodically.

In a modification of my invention shown in Fig. 2, the contact 4 is connected directly to the arm 63 and the contact 17 is directly connected to an arm 64, the free ends of the arms 63 and 64 being adjustably movable by adjusting screws 65 and 66. The compensating thermostatic elements 18 and 5 are omitted in this form. The element 14 is replaced by an element 61 to the upper end of which is pivotally attached as at 67, a generally horizontally disposed pawl 68 engaged with teeth of a ratchet wheel 69. The operation is generally the same as that of Fig. 1. Current flows from the source 60, through the winding 13 of the element 1, thence direct to the contact 3, thence to contact 4, through the arm 63 to a wire 10, to the arm 64, contact 17, contact 16, winding 62 and back to the source 60. A succession of impulses at the contacts 3—4 causes the contacts 16—17 to open, moving the pawl 68 ahead to another notch. Upon cooling of the element 61, it returns to its original position, closing the contacts 16—17 and during its return movement turns the ratchet wheel 69 the distance of the pitch of the teeth. The periodicity of the elements 1 and 61 may be adjusted by the screws 65 and 66 as will be understood from the more detailed description of Fig. 1.

In this form of my invention, the ratchet wheel 69 is mounted on a shaft 71 upon which is mounted a drum controller 72 having thereon one or more contacts 73—73 engageable by stationary contact fingers 74. A stationary finger 75 slides on the shaft 71. An external circuit comprising wires 76 and 77 is connected respectively to the fingers 74 and 75. A step-by-step rotation of the ratchet wheel 69 and shaft 71 successively brings the contacts 73 into contact with the finger 74, and then current may flow from a local source 78 through the finger 75, shaft 71, drum 72, contact 73, finger 74 and thence to an external circuit where an impulse of current thus sent out may be employed to actuate or control any desired and suitable apparatus. By the arrangement shown, two impulses will be sent out for each complete revolution of the ratchet wheel 69.

In the form of my invention shown in Fig. 2, a modified form of compensation for changes of ambient temperature is illustrated. In this form of my invention, it is presumed that the thermostatic elements 1 and 61 and their heaters 13 and 62 are disposed within an enclosing housing 90. Within the housing is also disposed a heating winding 80 for heating the air therein and for maintaining it substantially at a constant temperature. The heating winding 80 is placed in series with a contact 81 on an adjusting screw 82, a contact 83 engaging the contact 81, a bimetallic thermostatic element 84 carrying the contact 83 on its free end and at its opposite end rigidly connected to a stationary base or support 85, the circuit being completed from the element 84 to the source 60 by a wire 86, and from the source to the winding 80 by a wire 87.

When the device is put in operation, current continuously flows from the source 60 through the winding 80 and contact 83—81. When the interior of the housing attains the desired temperature, the element 84 bends sufficiently to break the contact at 83—81 and heating of the winding 80 is discontinued until the temperature

falls below the desired value whereupon the element 84 again closes the contact 83—81 and supplies more heat to the winding 80.

One mode of operation of the heating element 80 and its associated parts is to adjust the screw 82 so that at some high or maximum local temperature such, for example, as a summer temperature of 90°, the contacts 83 and 81 will just be held open by the element 84. At any lower local temperature, the contacts 83—81 will close and stay closed until the heating winding 80 has raised the temperature in the casing up to the said 90°.

By keeping the temperature within the casing at a constant value in this manner, the local or ambient temperature to which the elements 61 and 1 are subjected does not vary and no compensation therefor is necessary.

It will be understood that the periodicity of the elements 1 and 14 of Fig. 1 or the elements 1 and 62 of Fig. 2 is not limited to any particular ratio. In the practice of my invention it is only necessary that the periodicity of the element 1 be greater than that of the element 14, or 61, as the case may be. I have therefore found it convenient to refer to the periodicity ratio of these elements as a ratio of one plus to one.

My invention is not limited to any particular type of casing for use in connection with the form of Fig. 2. At 90 I have indicated in cross-section an enclosing casing such as that referred to above in which all of the apparatus elements described hereinbefore are enclosed, the circuit wires 76 and 77 being led through the wall of the casing as indicated at 91. It will be understood, of course, that some of the elements of apparatus such, for example, as the current source 60 may be disposed outside of the casing.

Where the form of my invention shown in Fig. 1 is employed, it may be desirable to employ shields 91 and 92 respectively to shield the bimetallic element 5 from heat of the winding 13 and to shield the bimetallic element 18 from heat of the winding 26. The purpose of these shields is to render the bimetallic elements 5 and 18 responsive only to ambient temperatures.

In both of the forms of Figs. 1 and 2, I have shown the circuits of the heating windings in series with each other and with the contacts controlled by the two thermostatic elements and with a common source of current, that is to say, all in a single continuous series circuit. My invention is not limited to this particular circuit arrangement. Those skilled in the art may devise circuits in which some of the elements referred to are in derived or parallel circuits without sacrificing the advantages of my invention. I have illustrated a single series circuit herein for purposes of description, that being the simplest circuit whereby my invention may be practiced.

From the foregoing disclosure of my invention, it will be apparent that it may be employed variously in relation to the passage of time either to measure intervals of time and to indicate the same as, for example, on a clock dial, or to perform an initiating or controlling function periodically after the passage of preselected intervals of time. My invention furthermore may be adapted to perform other functions involving time than those mentioned. I have found it convenient to refer to all of the possible time related functions of my invention as "timing" functions.

My invention is not limited to the exact details of construction nor to the exact circuit connections hereinbefore illustrated and described, and

it will be understood that many changes and modifications other than those shown may be made without departing from the spirit of my invention or sacrificing its advantages.

5 I claim:

the first thermostat, a contact set controlled by movement of the second thermostat, and a circuit connecting the source, the two heaters and the two sets of contacts in series relation, the thermostats being movable to periodically make and break the circuit at their respective contact sets responsive to changes of heating effect of their respective heaters, the ratio of periodicity of the thermostats being as one plus to one, electrically actuable time indicating means and an energizing circuit having contacts therefor controlled by movement of the thermostat of lower periodicity. 5
10
15

7. In an electric timing system, a current source, a first thermostat, an electric heater therefor, a second thermostat, an electric heater therefor, a contact set controlled by movement of the first thermostat, a contact set controlled by movement of the second thermostat, and a circuit connecting the source, the two heaters and the two sets of contacts in series relation, the thermostats being movable to periodically make and break the circuit at their respective contact sets responsive to changes of heating effect of their respective heaters, the ratio of periodicity of the thermostats being as one plus to one, electrically actuable time indicating means, and an energizing circuit and contacts therefor controlled by the contact of the thermostat of lower periodicity. 20
25

8. In an electric timing system, a current source, a first thermostat, an electric heater therefor, a second thermostat, an electric heater therefor, a contact set controlled by movement of the first thermostat, a contact set controlled by movement of the second thermostat, and a circuit connecting the source, the two heaters and the two sets of contacts in series relation, the thermostats being movable to periodically make and break the circuit at their respective contact sets responsive to changes of heating effect of their respective heaters, the ratio of periodicity of the thermostats being as one plus to one, and thermostat periodicity adjusting means for at least one of the thermostats.

9. In an electric timing system, a current source, a first thermostat, an electric heater therefor, a second thermostat, an electric heater therefor, a contact set controlled by movement of the first thermostat, a contact set controlled by movement of the second thermostat, and a circuit connecting the source, the two heaters and the two sets of contacts in series relation, the thermostats being movable to periodically make and break the circuit at their respective contact sets responsive to changes of heating effect of their respective heaters, the ratio of periodicity of the thermostats being as one plus to one, and thermostat periodicity adjusting means for both of said thermostats. 45 50 55 60

10. In an electric timing system, a current source, a first thermostat, an electric heater therefor, a second thermostat, an electric heater therefor, a contact set controlled by movement of the first thermostat, a contact set controlled by movement of the second thermostat, and a circuit connecting the source, the two heaters and the two sets of contacts in series relation, the thermostats being movable to periodically make and break the circuit at their respective contact sets responsive to changes of heating effect of their respective heaters, the ratio of periodicity of the thermostats being as one plus to one, and thermostat periodicity adjusting means for at least one of the thermostats comprising a movable support for one of the contacts of the set and means for adjustably moving the support. 75

11. In an electric timing system and apparatus, a thermostat, an electric heater therefor, and automatic means including a variable source of current, a heater circuit, electrical connections for periodically energizing the heater from the source with successive amounts of electric heat energy to effect periodic movement of the thermostat and compensating means for current variations, causing the cumulative value of the successive amounts of energy in a given interval to be substantially constant to cause the periodicity of the thermostat to be substantially constant.
12. In an electric timing system and apparatus, a thermostat, an electric heater therefor, and automatic means including a variable source of current, a heater circuit, electrical connections for periodically energizing the heater from the source with successive amounts of electric heat energy to effect periodic movement of the thermostat and heat responsive means operable by the current source causing the cumulative value of heating current supplied to the heater in a given interval to be substantially constant, a movable time indicating apparatus and means transmitting movement of the thermostat to the time indicating apparatus.
13. In an electric timing system and apparatus, a thermostat, an electric heater therefor, and automatic means including a variable source of current, a heater circuit, electrical connections for periodically energizing the heater from the source with successive amounts of electric heat energy to effect periodic movement of the thermostat and heat responsive means operable by the current source causing the cumulative value of heat energy supplied to the thermostat heater in a given interval to be substantially constant, and a time indicating apparatus operable by the movement of the thermostat.
14. In an electric timing system and apparatus, a thermostat, an electric heater therefor, and automatic means including a variable source of current, a heater circuit and electrical connections for periodically energizing the heater from the source with successive amounts of electric heat energy to effect periodic movement of the thermostat and for causing the cumulative value of the successive amounts of energy in a given time interval to be substantially constant to cause the periodicity of the thermostat to be substantially constant, an electric time indicating apparatus and a circuit therefor controlled by movement of the thermostat.
15. In an electric timing system and apparatus, a thermostat, an electric heater therefor, and automatic means including a variable source of current, a heater circuit and electrical connections for periodically energizing the heater from the source with successive amounts of electric heat energy to effect periodic movement of the thermostat and for causing the cumulative value of the successive amounts of energy in a given time interval to be substantially constant to cause the periodicity of the thermostat to be substantially constant, and contacts controlled by movement of the thermostat for making and breaking the heater circuit.
16. In an electric timing system and apparatus, a thermostat, an electric heater therefor, and automatic means including a variable source of current, a heater circuit and electrical connections for periodically energizing the heater from the source with successive amounts of electric heat energy to effect periodic movement of the thermostat and for causing the cumulative value of
- successive amounts of energy in like predetermined time intervals to be substantially equal to cause the periodicity of the thermostat to be substantially constant, contacts controlled by movement of the thermostat for making and breaking the heater circuit, and movable mechanical means for adjusting the position of one of the contacts to adjustably vary the periodicity of the thermostat.
17. In an electric timing system and apparatus, a thermostat, an electric heater therefor, and automatic means including a variable source of current, a heater circuit and electrical connections for periodically energizing the heater from the source with successive amounts of electric heat energy to effect periodic movement of the thermostat and for causing the cumulative value of successive amounts of energy in like predetermined time intervals to be substantially equal to cause the periodicity of the thermostat to be substantially constant, contacts controlled by movement of the thermostat for making and breaking the heater circuit, and movable mechanical means for adjusting the position of one of the contacts to adjustably vary the periodicity of the thermostat, and adapted to indicate by its position the said periodicity.
18. In an electric timing system and apparatus, a pair of thermostats, an electric heater for each thermostat, a current source, circuit connections for energizing the thermostats from the source, and contacts openable and closable by the movement of each thermostat to effect energization and de-energization of both heaters concurrently.
19. In an electric timing system and apparatus, a pair of thermostats, an electric heater for each thermostat, a current source, circuit connections for energizing the thermostats from the source, and contacts openable and closable by the movement of each thermostat to effect energization and de-energization of both heaters, opening of the contacts being adapted to concurrently effect the de-energization of both heaters, the thermostats moving periodically responsive to the energization and de-energization of their heaters, the periodicity of one thermostat being greater than that of the other, a movable time indicating apparatus and means transmitting movement of the thermostat of lower periodicity to the time indicating apparatus.
20. In an electric timing system and apparatus, a pair of thermostats, an electric heater for each thermostat, a current source, circuit connections for energizing the thermostats from the source, and contacts openable and closable by the movement of each thermostat to effect energization and de-energization of both heaters, opening of the contacts being adapted to concurrently effect the deenergization of both heaters, the thermostats moving periodically responsive to the energization and de-energization of their heaters, the periodicity of one thermostat being greater than that of the other, a movable time indicating apparatus and means transmitting movement of the thermostat of lower periodicity to the time indicating apparatus.
21. In an electric timing system and apparatus, a pair of thermostats, an electric heater for each thermcstat, a current source, circuit connections for energizing the thermostats from the source, and contacts openable and closable by the movement of each thermostat to effect energization and de-energization of both heaters, opening of either of said contacts being adapted to concurrently deenergize both heaters, the thermostats

moving periodically responsive to the energization and de-energization of their heaters, the periodicity of one thermostat being greater than that of the other, an electric timing apparatus and a circuit and circuit contacts therefore openable and closable by movement of the thermostat of lower periodicity.

22. In an electric timing system and apparatus, a pair of thermostats, an electric heater for each 5 thermostat, a current source, circuit connections 10 for energizing the thermostats from the source,

and contacts associated with each thermostat openable and closable by the movement of its associated thermostat to effect energization and de-energization of both heaters, opening of either contact being adapted to de-energize both heaters, the thermostats moving periodically responsive to the energization and de-energization of their heaters, the periodicity of one thermostat being greater than that of the other.
